(57) **CLAIM**

I claim the ornamental design for a robot dragon, as shown and described.

DESCRIPTION

FIG. 1 is a front perspective view of a robot dragon.

FIG. 2 is a side view of the right side of the robot dragon of FIG. 1.

FIG. 3 is a side view of the left side of the robot dragon of FIG. 1.

FIG. 4 is a top view of the robot dragon of FIG. 1.

FIG. 5 is a bottom view of the robot dragon of FIG. 1.

FIG. 6 is a rear view of the robot dragon of FIG. 1; and,

FIG. 7 is a front view of the robot dragon of FIG. 1. The dashed lines in various figures are for illustrative purposes only and form no part of the claimed design.
